MANUFACTURE OF ROADS, YARDS, AERODROMES, AND THE LIKE SURFACES

John Charles Telford, Westminster, London, and
John Hines, Barnes, London, England, assignors
to Braithwaite and Company Engineers Limited, London, England

Application March 25, 1932, Serial No. 601,142
In Great Britain November 30, 1931

9 Claims. (Cl. 94—8)

The present invention has for its object the provision of a strong foundation for road or the like surface suited to modern traffic conditions which can be rapidly produced by comparatively unskilled labour and with little or no interruption by the weather.

The foundation in accordance with the invention comprises two spaced layers of metal plating having concrete or like cementitious material sandwiched between them and is primarily characterized by the use of shear members between the metallic layers. The shear members are rigidly attached to the plating of both layers and prevent such relative lateral movement between the layers as is the normal result of the bending or flexing of the two layer metallic sandwich foundation under load. The shear members may be made sloping so as to resist the shear forces in a similar manner to the diagonal web members of a lattice girder; also they may be arranged to be inclined in varying directions so as to be effective in resisting the forces in these directions. For instance in its simplest form a shear member comprises a strap with end flanges secured to the layers of plating and set at such an angle to the main part of the strap that the latter is properly inclined. Oppositely inclined straps may be used in pairs so that the stresses from opposite directions are resisted by each pair.

In a convenient method of construction the inclined straps of each pair may be combined to form a distance piece of box-like or frame-like form which may be produced from metal strip bent to trapezoidal shape and disposed so that the layers of plating may be secured respectively to opposite parallel sides. When the distance pieces are constructed in this manner and suitably arranged between the layers of plating they serve not only to take up the shear stresses satisfactorily when the roadway is in use, but also to maintain the spacing of the layers at a predetermined distance, so that whilst the concrete is hardening, materials may be stored on the top layer.

In an alternative method of construction the pairs of sloping shear members are employed each in the form of a strap bent once along its length to form a stirrup or arch the feet of which are rigidly attached, for instance by welding, to the bottom layer of plating. The top layer of plating is formed with slots through which the upwardly directed angles of the stirrups project. A wedge is then inserted between the top plating and the projecting arch of each stirrup so that the ends of the slot are forced

downwardly on to the sloping legs of the stirrup and may be rigidly secured thereto by welding. This method has the advantage that no workmanship whatever is required on the bottom plating and from a constructional point of view there is the additional advantage that each leg of the stirrup shear member is in direct tension between two welds. It will be seen that this alternative construction with stirrup shear members does not involve the use of bolts to which the average road making labourer is not accustomed.

In the construction of a foundation in accordance with the invention it is preferable to arrange for the parts to be assembled at the site and accordingly the metallic layers should be built up from individual plates of a size convenient for transport and manipulation and designed to be interconnected along their edges in situ to form substantially continuous courses that are capable of retaining the filling material between them. The flat plates for use in the present method need have no projections or attachments before reaching the site and accordingly occupy the minimum amount of space during transport. They are preferably ready formed however, with any necessary holes for use both with the attachments between the layers and in the method of anchorage with the subsoil described more particularly below.

The site where it is proposed to lay the road or like foundation is, if necessary, prepared by the surface material being first levelled and the subsoil consolidated by rolling. The consolidated subsoil may then be covered with a layer of sand, ground clinker or other suitable material to form a bed for the lower layer of plating.

The invention will now be particularly described with reference to the accompanying drawings wherein:

Figure 1 is a plan view of a number of assembled plates connected by one form of shear distance piece, three plates being shown in the upper layer and six in the lower layer for convenience in illustration.

Figure 2 is a section on an enlarged scale along the line 2—2 of Figure 1.

Figure 3 is an isometric view in part broken away of an assembly of plates with curb or buttress plates along one edge thereof.

Figure 4 is a section through an edge part of the foundation showing the connection of the upper and lower plates with a curb plate.

Figures 5 and 6 are section and plan view respectively of the kind of shear distance piece employed in the arrangement illustrated in Fig-

ures 1 to 3 shown on a larger scale in position between the layers of plating and in association with a securing bolt.

Figure 7 is a section of a similar distance piece 5 secured to the plating by welding.

Figure 8 is a plan view of a number of assembled plates connected by stirrup shear members, two plates being shown in the upper layer and four in the lower layer.

10 Figures 9 and 10 are respectively an end elevation and a side elevation of a stirrup shear member in position between the layers of plating, and.

Figure 11 is a diagrammatic view of the simplest form of shear member.

The simple distance piece or shear member illustrated more or less diagrammatically in Figure 11 comprises a strap *a* with end flanges *b* and *c* secured to the upper and lower layers of plating respectively. The flanges are set at such an angle to the main part of the strap that the latter is most efficiently inclined for taking up shear stresses. Another identical strap *d* shown in chain dotted lines may be oppositely inclined to resist stresses in the other direction.

One preferred method of building up a foundation in accordance with the invention is illustrated in Figures 1 to 7 to which the following description relates:

30 It is desirable to lay the plates forming the bottom layer in the following manner. Referring to Figure 3 the edge of the road is first defined by vertical plates 1 constituting a curb or buttress preventing the spread of the bed under load
35 or the washing away of the subsoil by water which would result in the destruction of the foundation. Adjacent curb plates 1 may be interconnected by butt straps 2 and the tops of the plates may be inwardly turned substantially at right angles to form a flange 3 for purposes of interconnection with the top layer of plates.
40 After the curb plates are in position the laying of the bottom plates adjacent to the curb is proceeded with. The plates 4 of the first row are preferably flanged as shown by the reference numeral 5 to facilitate their attachment with the curb. This attachment not only serves to tie in the curb, but also accurately locates the first row of plates. The plates 6 subsequently
45 laid down are progressively located from the first row by means of spikes 7 (see especially Figure 2) driven through registering holes 8 near the edges of adjacent plates and into the subsoil. The holes in each plate which are provided for this purpose are preferably symmetrically arranged.
50 They are conveniently four in number and are disposed at a distance of one quarter the length of the plate measured from the ends along both longitudinal edges. In this way adjacent rows of plates can readily be relatively positioned with
55 the plates of one row staggered with respect to those in the next adjoining row. Also owing to the symmetry of the arrangement of the holes, it is immaterial which side of a plate is uppermost or in which direction it is turned.

As already mentioned the plates are delivered to the site without any attachment, and the distance pieces are secured thereto before the plates are carried to the actual road bed. These distance pieces are preferably delivered as complete units. In a convenient form of construction illustrated in Figures 5, 6 and 7 they are produced by welding together the free ends of two angle members of strip metal, one a short length 9 with outwardly directed flange ends 10 and the

other a longer piece 11 with inwardly directed flanged ends 12 adapted to meet the flanges of the first member and to be secured thereto by welding. In this manner a trapezoidal boxlike frame structure is obtained with opposite parallel sides, one longer than the other, for rigid attachment to the top and bottom plates respectively. If desired each distance piece may be made from a single strip bent to shape with its ends welded together. The sides slope in accordance with which way up the distance piece is employed; it may be desirable for some to have the broad base attached to the bottom plate and some the narrow. The distance pieces may be attached to the bottom layer either by welding or by bolting or other known method, the number used and their disposition being the same in either case. Where bolts are used throughout, the plates must be provided with bolt holes. In a plate measuring approximately 6 feet by 4 feet it is desirable for sixteen such holes to be arranged symmetrically in four rows as shown best in Figures 1 and 3. The symmetry of the arrangement is optional but is designed to ensure complete reversibility of the plates and consequent simplicity in assembly. It is preferable to adopt the arrangement illustrated wherein the corner distance pieces 13 are diagonally arranged and associated with bolts so that the plates of the top layer may be located as subsequently described. The remaining distance pieces are secured by welding only, some 14 being arranged longitudinally of the plates and others 15 transversely to take up the stresses in these directions.

The distance pieces 13 shown in Figures 5 and 35 6 for bolting to the plates are provided with bolt holes 16 and 17 opposite one another in the parallel sides or seatings 9 and 11 respectively. The bolts 18 employed are inserted from the underside of the bottom plate through holes 19 40 and are sufficiently long to project through the distance piece and above the top plate when the projections 20 act ultimately as a bond or key for the top dressing or surfacing—preventing creep. After the insertion of the bolt through the bottom plate the bottom seating of the distance piece 45 is threaded thereon and a nut 21 screwed on to the bolt. The nut is tightened against the bottom seating whilst the free end of the bolt is caused to project through the hole in the top seating for subsequent engagement with a plate 22 in the top layer. In an alternative method shown in Figure 7 the distance pieces may be welded to the bottom plates at appropriate positions. Those distance pieces nearest the corners of 55 each bottom plate, are, however, bolted in the manner already described (in addition to welding if desired), so as to provide a definite location for the top plates by means of the projecting bolts 20. In those places where welding only 60 is relied on, it is of course not necessary to provide bolt holes.

After the bottom layer of plates is completely laid it is, in the case of a road, finished off on the opposite edge with a second curb of the kind already described, and the edges of all the plates are then preferably secured by welding at intervals. The concrete 23 is then filled in to the depth of the distance pieces and the addition of the top layer of plating is put in hand. The individual plates 22 of the top layer and those of the bottom layer are staggered in every possible sense so that the junctions between the plates in one layer are nowhere opposite the junctions in the other, thus adding materially to the 70 75 65

strength of the assembled structure. The edge plates 24 of the upper layer are secured to the top flanges of the curb plates referred to previously. The holes 25 provided in the top plates 5 are designed to lie opposite the distance pieces. They are preferably made considerably larger than the securing bolts 18 and may be with advantage as much as of three times greater diameter, so as to allow for any inequalities which may 10 occur in the laying out of the top plates. This hole is designed to be covered by a washer plate 26 around the bolt 18 and resting on the top plate 22, to which its edges can be welded in situ as shown in Figure 5. A second securing nut 27 is 15 then tightened on to the projecting bolt shank and bears on top of the washer 26. By this arrangement the top plate can be readily removed without damage, the sandwiched concrete cut away and the lower plates taken up in case it is necessary to gain access to drains, cables and 20 the like under the foundation. In cases where the top plate is welded to the distance piece, the relatively large hole 25 already mentioned, permits of the welding of the top plate from above, 25 directly on to the top seating of the distance piece part of which is uncovered by the hole as shown in Figure 7. As in the case of the bottom layer of plates, those of the top layer are designed to overlap one another slightly and may be interconnected along the edges by welding at 30 intervals.

The alternative method of construction illustrated in Figures 8 to 10 involves the use of shear members in the form of stirrups or arches 28 each formed from a length of metal strip bent conveniently to a right angle at the middle of its length so as to form two sloping legs 29. The plates 30 of the bottom layer are delivered to the site unworked and the feet 31 of the stirrups are then secured thereto by welding with the angles 32 upwardly projecting. A regular diagonal disposition of the stirrups is shown in Figure 8 and is found in practice to be a desirable arrangement. The lower layer of plating is 40 then laid and the concrete is filled in around the stirrups. The plates 33 of the top layer are formed with short slots 34 through each of which the angular summit of one of the stirrups projects, the ends 35 of the slot resting respectively 45 on the sloping legs 29 of the stirrup. Between the angular arch 32 of the stirrup and the plate 33 a wedge 36 is driven transversely of the slot thus holding the top plate in position and exerting tension on the legs of the stirrup. Whilst 50 the parts are still in tension the ends 35 of the slot are welded to the sloping legs 29.

The completed foundation is designed to be used for supporting a top layer of any suitable road surfacing material such as a bituminous 55 macadam, stone sets, rubber or the like.

It is to be appreciated that any flexing of the structure under load while in actual use, would lead to a slip or relative horizontal sliding movement between the plating and filler and such movement will quickly lead to a breakdown of the foundation if not prevented. By the construction described, certain of the devices between the platings and embedded in the filler 60 are so formed and constructed as to absorb this relative horizontal and shearing movement and prevent such as objectionable movement. As such relative horizontal and shearing movement is thus absorbed in the structure itself, it is apparent that said structure cannot sag or flex 65

under the load it is designed or intended to bear.

We claim as our invention:

1. A road or like foundation embodying therein spaced metallic platings, devices for holding said platings in spaced relation, certain of said devices comprising inverted substantially V-shaped stirrups, each having feet welded to the bottom plating and having its bend or crotch upwardly directed to extend through an opening in the top plating. 5

2. A road or like foundation embodying therein spaced metallic platings, devices for holding said platings in spaced relation, certain of said devices comprising inverted substantially V-shaped members each having feet welded to the bottom plating and having its bend or crotch upwardly directed to extend through associated openings in the top plating and wedges engaged with said bend or crotch of said members above said top plating and which wedges force the top 10 plating downwardly to bring portions of said openings into engagement with the legs of said inverted V-shaped members. 15

3. A road or like foundation embodying therein spaced top and bottom metallic platings, there being openings in the top plating, and inverted V-shaped members for holding said platings in spaced relation, certain of said portions of said top plating defining said openings being welded to parts of the legs of said inverted V-shaped 20 members. 25

4. A road or like foundation embodying therein, spaced separate top and bottom thin metallic flexible platings, a filler of rigid cementitious material therebetween, and devices, certain ones of 30 which are operatively connected at their top end to one of said platings and other ones of which devices are operatively connected at their bottom end to the other of said platings, said devices being embedded in said filler and so formed and 35 so arranged in said filler as to absorb horizontal stresses in any lateral direction as induced by the tendency of relative slipping movement between said platings and filler. 40

5. A road or like foundation embodying therein, spaced top and bottom platings, a filler of rigid cementitious material therebetween, devices operatively connected at their top and bottom portions to said platings and embedded in said 45 filler, said devices being so formed and so arranged as to absorb horizontal stresses in any lateral direction as induced by the tendency of relative slipping movement between said platings and filler, and vertical curb plates closing the 50 structure at each side thereof and formed to project downward into the subsoil upon which the structure is laid. 55

6. A road or like foundation embodying therein, spaced top and bottom platings, a filler of rigid cementitious material therebetween, devices operatively connected at their top and bottom portions to said platings and embedded in said 60 filler, said devices being so formed and so arranged as to absorb horizontal stresses in any lateral direction as induced by the tendency of relative slipping movement between said platings and filler, vertical curb plates closing the structure at each side thereof and to which said top and bottom platings are secured and which curb plate is formed to extend downwardly below the 65 bottom plating and into the subsoil upon which said structure is laid. 70

7. A road or like foundation embodying therein, spaced top and bottom platings, a filler of rigid cementitious material therebetween, devices 75

operatively connected at their top and bottom portions to said platings and embedded in said filler, said devices being so formed and so arranged as to absorb horizontal stresses in any lateral direction as induced by the tendency of relative slipping movement between said platings and filler, vertical curb plates closing the structure at each side thereof and formed to project downward for engagement in the subsoil upon which the structure is laid, said platings and curb plates having associated flanges operatively connected together.

8. A road foundation comprising spaced separate top and bottom thin metallic flexible platings, a cementitious filler between said platings, and shearing stress absorbing devices embedded in said filler, certain of said devices being engaged with the top plating and extending toward the bottom plating and other of said devices being engaged with the bottom plating and ex-

tending toward the top casing, and means for securing said platings and said devices together in operative relation.

9. A road or like foundation embodying there-in spaced apart top and bottom flexible metallic platings, a filler of rigid cementitious material therebetween, devices connecting said platings together in operative relation and being anchored in the cementitious material, said devices being arranged in groups disposed in various directions, with each device comprising straight sloping parts to absorb horizontal stresses, there being at least one group of said devices arranged with their sloping parts directed toward one of the major directions of horizontal lateral stresses as induced by the tendency of a relatively slipping movement between said platings and filler.
